UNITED STATES PATENT OFFICE.

DORA RAND, OF KIRKLAND, ILLINOIS.

IRONING-BOARD ATTACHMENT.

1,192,225.

Specification of Letters Patent. Patented July 25, 1916.

Application filed April 15, 1916. Serial No. 91,358.

To all whom it may concern:

Be it known that I, DORA RAND, a citizen of the United States, residing at Kirkland, in the county of Dekalb and State of Illinois, have invented new and useful Improvements in Ironing-Board Attachments, of which the following is a specification.

This invention relates to ironing boards, and more particularly to an attachment 10 therefor.

The object of the invention is the provision of a device of the above stated character, wherein the attachment is so positioned with respect to the board to prevent the engagement or dragging of the overhanging edges 15 of the clothes being pressed upon the board, with the floor surfaces, and thereby preventing the soiling of the same.

With the above and other objects in view, 20 the invention consists in the novel features, details of construction and combination of parts which will hereinafter be more fully set forth, illustrated in the accompanying drawing, and pointed out in the appended 25 claim.

Figure 1 is a perspective view of an ironing board, showing my improved attachment applied thereto, and in active use; Fig. 2 is a bottom plan view of the ironing board 30 illustrating the manner of connecting the supporting arms with the apertured plates; and Fig. 3 is a perspective view of one of the supporting arms.

Referring more particularly to the accompanying drawing, in which like characters of 35 reference refer to corresponding parts in the several views, 5 denotes the usual ironing board having connected therewith an attachment, designated generally by the character 40 6, and the purpose of such attachment is to so position the same with respect to the board, whereby upon the pressing of table cloths, linen sheets, draperies and other large pieces of clothes, the clothes will be prevented from dragging or contacting with 45 the floor surfaces. The said attachment 6 comprises a plurality of plates 7, adapted to be secured in pairs to the underneath surface of the ironing board at points adjacent the

50 opposite ends of the boards, and each of said plates 7 is formed with an opening 8. The purpose of this plate 7 serves to support to the bottom surface of the board a plurality of supporting arms 9. Each of the supporting arms embodies a flexible rod 10 formed

with an offset inner extremity 11, adapted to be inserted in the opening 8 of the plates for supporting the arms on said plates, and positioning the arms in pairs, and extending the same in a horizontal plane with respect to the ironing board 5, and beyond the opposite longitudinal edges 12 thereof, as at 13. A pair of clothes holding members 14 are provided for receiving the opposite overhanging edges of the clothes being pressed upon the board, and for the purpose of illustration, the same is shown as comprising a large linen sheet 15. These clothes holding members each comprises a linen bag 16 provided on the upper edges 17 thereof with loops 17 for receiving the extending ends 13 of the supporting arms 9, and thereby holding the bags 16 in suspended position with respect to the board 5. It will be further observed that these bags 18 by being positioned in a plane with respect to the length of the board and to opposite sides thereof, will permit of both extremities or ends of the cloth 15 being pressed upon the board to be supported free of contact 19 from the floor surfaces, and thereby preventing the soiling of the cloth 15 before and after the same has been properly pressed. In order to prevent any accidental swinging movements of the supporting arms 9 when in 25 active position, I provide the plates 7 with ribs 18, thereby assuring said supporting rods against movement with respect to said plates.

From the foregoing description, taken in 20 connection with the accompanying drawing, the advantages of construction and of the method of operation will be readily apparent to those skilled in the art to which the invention relates, and while I have described the principles of operation of the invention, together with the device which I now consider to be the best embodiment thereof, I desire to have it understood that the device shown is merely illustrative, and 25 that such advantages may be made when desired as are within the scope of the claim appended thereto.

I claim:

An attachment for ironing boards embodying a series of plates each having an aperture, a plurality of supporting arms, each formed with an offset end, the offset end of the supporting arms being inserted in the openings of said plates for detachably 110

connecting said arms thereto and disposing the same at right angles with respect to the opposite side edges of the board, and a bag formed at its opposite ends with loops for receiving the projecting ends of the supporting arms and disposing the bag to opposite sides and in a longitudinal plane with respect to the side edges of the board, to prevent the contact of the overhanging portions

of the clothes being pressed with the floor surfaces.

In testimony whereof I affix my signature in presence of two witnesses.

DORA RAND.
